UNITED STATES PATENT OFFICE.

MAX WEBER, OF DETROIT, MICHIGAN.

MANDOLIN ATTACHMENT FOR PIANOS.

Application filed October 27, 1924. Serial No. 746,021.

To all whom it may concern:

Be it known that I, MAX WEBER, a citizen of the United States, residing at Detroit, in the county of Wayne and State of Michigan, have invented a new and useful Improvement in a Mandolin Attachment for Pianos, of which the following is a specification.

My invention relates to a new and useful improvement in a mandolin attachment for pianos and such other instruments as comprise a plurality of strings adapted for striking with an actuating hammer and the like.

The invention, as shown in the drawings, is applied to a piano and may be used with a silent piano or a mechanical piano.

An object of the invention is to provide a mechanism which may be brought into engagement with a plurality of strings of the piano at the will of the operator, so as to produce, while the piano is being played, an effect whereby the music rendered resembles that produced by a mandolin.

It is an object of the invention to provide a construction and arrangement of such a device whereby the device may be used by the operator when desired and will in no way injure the piano, or affect the music of the piano when the device is in inoperative position.

It is another object of the invention to provide in a device of this class a plurality of contact members loosely mounted and adapted for suspension in close proximity to the strings of the piano, so as to be engaged by the strings when the strings themselves are set in vibration by the hammers of the piano. In this structure, the hammers do not strike the engaging members, the arrangement and construction of the invention being such that the usual operation of the hammers and the operation of the actuating mechanism of the piano in general is not in any way interfered with. The method of mounting the loosely suspended engaging members is such that there is no probability of their becoming wound around the strings of the piano or caught between the strings.

It is another object of the invention to provide a plurality of engaging members adapted for engagement when in a certain position with the vibrating strings of the piano and so suspended that they may vibrate at different velocities depending upon the vibration of the strings of the piano with

which they engage. The number of times the engaging members engage against the strings will be determined solely by the variation in the vibrations of the strings themselves and results from the loose and free mounting of the engaging members.

Another object of the invention is the provision of a device of this class which may be brought into operative position or moved to inoperative position by the operator at will irrespective as to whether the piano is being played or not at the time of movement of the device from either position to the other. This is brought about because of the specific structure and arrangement of the device and complete non-disturbance of the actuating and operating mechanism of the piano in general.

Another object of the invention is the provision of a device of this class which will be simple in structure so that it may be easily, quickly and properly installed by an ordinary piano mechanic.

Other objects will appear hereinafter.

The invention consists in the combinations and arrangements of parts hereinafter described and claimed.

The invention will be best understood from a reference to the accompanying drawings, which form a part of this specification, and in which,

Fig. 1 is a fragmentary top plan view of the sounding board of a piano showing a portion of the strings and illustrating the invention in mounted position in side elevation.

Fig. 2 is a sectional view taken on substantially line 2—2 of Fig. 1,

Fig. 3 is a sectional view taken on substantially line 3—3 of Fig. 1,

Fig. 4 is an enlarged fragmentary side elevational view illustrating the structure of the engagement members.

Fig. 5 is a sectional detail showing the attachment of the buttons.

In Fig. 1, I have shown the sides 9 and 9' of the piano casing extending between which is a sounding board 12. Projected over the sounding board 12 and suspended therefrom by the use of proper bridges are the piano strings 11 which engage the pressure bar 10. A brass tube, or supporting member, 13 is mounted in a suitable bearing 14, which is secured to one side of the piano casing 9, the opposite end of the tube,

2

or supporting member, 13 is supported by a suitable bearing 15, which is supported by a bracket 16 mounted on the action bracket bolt 17 of the piano. Projecting downwardly from the tube 13, over the middle section of the treble cleff are a plurality of tubes or supporting members 18, each of which has mounted upon it, adjacent its lower end and terminating with its lower end, a rubber tube 19. Forced into the lower end of the tube 18 is a block 19 adapted to clamp against the edge of the tube 18 a string 21 which is fastened to an eyelet 23, so as to support in free swinging relation to the tube 18 the engagement members 22. For the purposes of this specification, these engaging members 22 shall hereafter be termed "buttons", although it will be apparent, as the description proceeds, that any suitable contact or engagement member may be substituted for the specific form of button which I have shown. Mounted at one end in a suitable bearing 25 which it attached to the side 9 of the piano casing is a brass tube 24, from which similarly arranged buttons depend, these buttons being suspended over the upper section of the treble cleff. The particular location and arrangement of the buttons may, of course, be varied but I have shown the buttons extended over the middle and upper sections of the treble cleff, inasmuch as the operation of the piano or musical instrument with which used will give better results with the engagement buttons in this position. Mounted upon the tube 13, adjacent one end, is a clamp 26, from which projects a rocker arm 27 pivotally connected to a tongue 28 which is, in turn, pivotally connected to the free end of a rocker arm 29 mounted fixedly upon a suitable shaft 30 from which projects an operating arm 31. The tube 13 is rotatably mounted in the bearings 14 and 15, so that the operator, upon engaging the arm 31, which extends in the roll box 32 of the piano, may rock the tube 13 by rocking the shaft 30, the illustration showing the invention applied to a player piano, although, as will appear from the description, it may be used on any standard piano, the arm 31 being placed in any accessible position. This rocking movement of the rod 13 will bring each of the buttons into such a position as to permit engagement of each of the buttons with its corresponding strings. Inasmuch as the buttons are freely suspended, as described, a vibration of the strings will cause the buttons to swing rapidly, the rapidity of their swinging depending upon the speed of vibration of the respective strings. When the buttons dance against the strings, the piano, or other musical instrument, will produce a mandolin effect, the music being substantially the same as produced by a mandolin. The but-

tons are of such size, that they cannot lodge between the strings and may engage either one of the strings at a time or more than one, depending upon their size and the particular position or direction of movement in response to the vibration of the strings. I have provided the rubber covering 19 on the rod 18, so that if the buttons should swing violently enough to strike their supporting member above the point of connection above the string 21 therewith, no sound will be given out, inasmuch as the rubber tube 19 will not, upon engaging the buttons, produce any sound. It is consequently seen that the covering of the lower portion of the tube 18 need not necessarily be a rubber tube 19 as any suitable soundless and sound deadening material would suffice. Fixedly mounted upon the tube 13 adjacent the side 9 of the piano casing is an arm 33 which projects downwardly and is adapted for remaining normally in engagement with an arm 34, which is fixedly mounted upon the tube 24, said tube 24 being rockingly mounted in the bearing 25, as shown in Fig. 3. The upper end 36 of the arm 34 is curved so that the arm 33 will lie in engagement with a curved portion of the arm 36. The construction is such that upon a rocking of the tube 13, the arm 33 is rocked downwardly which serves to rock the arm 34 to rock the tube 24, so as to bring the engaging buttons which are suspended from the tube 24 into operative position relatively to the wires 11 over which positioned. The operation of these engaging buttons with the strings is the same as already described for the engaging buttons mounted on the tube 13. As shown in Fig. 3, the hammer 37, which is used to strike the strings, is adapted for engagement with the strings between the tubes 13 and 24, the line of engagement of the hammers 37 with the strings being indicated by the dotted line 38 in Fig. 1. It is apparent, however, that these tubes may be placed in different position relatively to the striking line 38 of the hammers 37, so long as the tubes and the suspended buttons are not in such a position as to be engaged by the hammer 37. When the operator desires to rock the tube 13, so as to bring the buttons into non-operative position, as shown in full lines in Fig. 3, the spring 39, which is mounted on the bearing 24, will, with its engagement with the arm 34, rock the tube 24, so as to move it to the position shown in full lines in Fig. 3, the position of the buttons shown in dotted lines in Fig. 3, indicating the operative position of the buttons.

is in engagement with the arm 34, so that, when the tube 24 is rocked to operative position, the spring is placed under tension.

While I have illustrated and described the 5 preferred form of construction, I do not wish to limit myself to the precise construction shown but desire to avail myself of such variations and modifications as come within the scope of the appended claims.

Having thus described my invention, what 10 I claim as new and desire to secure by Letters Patent is:

1. A device of the class described adapted 15 for use with stringed musical instruments, comprising a supporting member extending across the strings of said instrument; a plurality of suspension members mounted on said supporting member; and contact buttons mounted on said suspension members in 20 free swingable relation thereto; means for covering the lower portion of said suspension members for preventing sound producing contact with said buttons, said supporting member being adapted for rocking 25 movement for bringing said buttons into engagement with said strings or moving the same out of said engagement.

2. A device adapted for use with a 30 stringed musical instrument, comprising a plurality of supporting members, adapted for rocking independently of each other; a plurality of freely swingable contact members carried by each of said supporting members; means for rocking said supporting members 35 simultaneously for bringing said contact members into engagement with the strings of said musical instrument.

3. A device adapted for use with a 40 stringed musical instrument, comprising a plurality of supporting members, adapted for rocking independently of each other; a plurality of freely swingable contact members carried by each of said supporting members; means for rocking said supporting 45 members simultaneously for bringing said contact members into engagement with the strings of said musical instrument; and manually operable means for rocking one of said supporting members for moving said 50 contact members out of engagement with

said strings; and resilient means for rocking the other of said supporting members for bringing the contact members carried thereby out of engagement with said strings.

4. An attachment for stringed musical 55 instruments, comprising a pair of independent supporting members; freely swingable contact members carried by each of said supporting members adapted for engagement with the strings of said musical instrument 60 when in operative position; a lever for rocking one of said supporting members for bringing said contact members into operative position; an arm mounted on said supporting member; an arm mounted on the other 65 supporting member and adapted for engaging said arm, said arms being co-operative for rocking the other said supporting member upon the rocking of said first mentioned supporting member. 70

5. An attachment for stringed musical instruments, comprising a rockingly mounted supporting member; a plurality of freely swingable contact members carried by said supporting member; an additional rockingly mounted supporting member; similar contact members carried by said additional supporting member; an arm fixedly mounted on said first mentioned supporting member; an arm fixedly mounted on said second mentioned supporting member having the free 75 end thereof curved and adapted for engagement with said first mentioned arm; means for rocking said first mentioned supporting member said arm on said supporting member being adapted for effecting the rocking of said second mentioned supporting member upon the rocking of said first mentioned supporting member; manually operable means for rocking said first mentioned supporting member to inoperative position; and resilient means for rocking said second mentioned supporting member to inoperative position upon the rocking of said first mentioned supporting member to inoperative position. 80 85 90 95

In testimony whereof, I have signed the foregoing specification.

MAX WEBER.
